UNITED STATES PATENT OFFICE.

HARRY E. WINTERS, OF DAVENPORT, IOWA.

DESIGN FOR A CASING FOR EGG-CANDLING DEVICES.

51,273.

Specification for Design.

Patented Sept. 11, 1917.

Application filed July 26, 1917. Serial No. 182,986. Term of patent 3½ years.

To all whom it may concern:

Be it known that I, HARRY E. WINTERS, a citizen of the United States, residing at Davenport, in the county of Scott and State of Iowa, have invented a new, original, and ornamental Design for Casings for Egg-Candling Devices, of which the following is a specification.

The figure is a projection on isometric lines, showing a casing for egg-candling devices, embodying my new design.

Said design comprises a pair of egg-shaped end-pieces, united by a shell conform-

ing in shape thereto, and provided with supporting legs.

I claim:

The ornamental design for a casing for egg-candling devices, as shown and described.

In testimony whereof I affix my signature in the presence of two witnesses.

HARRY E. WINTERS.

Witnesses:

W. N. HASKELL,
R. M. SOLBRIG.
